TELEPHONE PENCIL HOLDING-ACCESSORY

August Guardino, Flushing, N. Y.

Application March 15, 1955, Serial No. 35,050

Term of patent 14 years

(Cl. D26—14)

Fig. 1

Fig. 2

Fig. 3

Fig. 4

Fig. 1 is a front elevational view of a telephone pencil holding accessory, embodying my new design;

Fig. 2 is a rear elevational view;

Fig. 3 is a top plan view; and

Fig. 4 is a side elevational view.

I claim:

The ornamental design for a telephone pencil holding accessory, as shown.
